United States Patent Office

Des. 201,535
Patented June 29, 1965

201,535

SERVICE STATION DISPLAY CABINET OR SIMILAR ARTICLE

Joseph A. Winger, Myron R. Cothorn, and Murry J. Gammill, Greenwich, Conn., assignors to Texaco Inc., New York, N.Y., a corporation of Delaware

Filed Mar. 18, 1964, Ser. No. 79,062

Term of patent 14 years

(Cl. D80—11)

FIGURE 1 is a front elevational view of a service station display cabinet or similar article showing our new design;

FIGURE 2 is a right side elevation;

FIGURE 3 is a rear elevation view;

FIGURE 4 is a fragmentary transverse cross-section taken along the lines 4—4 of FIGURE 1 looking in the direction of the arrows;

FIGURE 5 is a left side elevation view; and

FIGURE 6 is a top plan view.

The dominant features of our design reside in the portions shown in full lines.

We claim:

The ornamental design for a service station display cabinet or similar article, as shown and described.
